DOOR KNOB OR SIMILAR ARTICLE

Norman D. Louis, Los Angeles, Calif., assignor to Ajax Hardware Manufacturing Corp., Los Angeles, Calif., a corporation of California

Application October 2, 1958, Serial No. 52,849

Term of patent 14 years

(Cl. D50—3)

FIG. 1.

FIG. 2.

FIG. 3.

FIG. 3.

FIG. 4.

Figure 1 is a front view of a door knob showing my new design.

Figure 2 is a side view of the door knob.

Figure 3 is a bottom view of the door knob.

Figure 4 is a perspective view of the door knob.

Figure 5 is a cross-sectional view of the door knob taken on the line 5—5 of Figure 1.

I claim:

The ornamental design for a door knob or similar article, as shown.
